DESIGN FOR A COMBINATION COOKING UTENSIL

John C. Johnson, Birmingham, Ala.

Application November 29, 1933. Serial No. 49,894

Term of patent 14 years

To all whom it may concern:

Be it known that I, JOHN C. JOHNSON, a citizen of the United States, residing at Birmingham, in the county of Jefferson and State of Alabama, have invented a new, original, and ornamental Design for a Combination Cooking Utensil, of which the following is a specification, reference being had to the accompanying drawing, forming part thereof.

Figure 1 is a perspective view of the combined cooking utensil showing my new design; Figures 2, 3 and 4 respectively are the three sections of the combination shown in Figure 1.

I claim:—

The ornamental design for a combination cooking utensil, as shown and described.

JOHN C. JOHNSON.
